SHIM

Waldo H. Blackmer, New York, N. Y., and Earle L. Young, Woodcliff, N. J., assignors to Laminated Shim Co., Inc., Long Island City, N. Y., a corporation of New York

Application November 30, 1932, Serial No. 644,970

12 Claims. (Cl. 308—244)

This invention relates to the manufacture of shims for use in connection with split bearings of internal combustion engines and other mechanical equipment in which the shim has a solid body portion to which is secured a soft face portion, which may be of babbitt or similar material and the invention more particularly relates to the manner by which the face portion is secured to the body portion.

10 It is one of the objects of this invention to provide a composite shim which may be of solid or laminated construction and which is provided with an embedded facing member of softer material which is secured to all of the body elements in interlocking arrangement to prevent loosening of the parts.

Another object of the invention is to provide a composite shim having a hard body portion and a softer facing portion in which the facing portion is more firmly interlocked and embedded with the body portion so as to prevent separation of the parts during shipment or due to expansion and contraction of the shim parts when in use in the bearing.

25 Another object of this invention is to provide a shim having a facing member secured to the body portion of the shim in which the body members all have planar front faces and in which the facing member is secured by interlocked and dovetailed grooves and may be equally as well secured throughout the front face or merely at the edge portions of the shim.

Another object of this invention is to provide a composite shim having a softer metal facing member in which the shim body portion is composed of a plurality of individual sections of substantially identical outline and the same principal dimensions, but in which certain of the sections are reversed with respect to other sections to afford an interlocked and embedded connection for the facing member.

Another object of this invention is to provide a composite shim for bearing members in which the facing member will be interlocked and retained in embedded relation with the body members and in which the major dimensions of all of the body members are substantially equal, but in which the body members may have differently shaped and spaced projections so that when assembled, the resultant recesses for receiving the softer facing material will be irregular and provide interlocks for the facing material.

Another object of this invention is to provide a compound shim with a critical plane face for all the elements, certain of the elements having

different recesses whereby the composite shim will offer a series of irregular openings for interlocking the facing metal.

Another object of this invention is to provide a composite shim for bearings in which the solid body portion is not limited to brass but may be of steel or other material inasmuch as the irregular projections of the face afford such interlocking recesses that the Babbitt metal facing will be secured to the body irrespective of the adhesion of the facing metal to the body material.

Various other objects and advantages of this invention will appear from the following description thereof taken in connection with the attached drawings which illustrate preferred forms of embodiment thereof and in which:

Figure 1 is a side elevation of one form of shim of composite form and having a babbitted facing portion.

Figure 2 is an end elevation of the shim shown in Figure 1.

Figures 3 and 4 are leaves or sections of a shim, Figure 4 being the reverse of Figure 3.

Figure 5 is a side elevation of a partially completed shim formed of a plurality of similarly shaped elements shown in Figures 3 and 4 in which the intermediate element is in the position shown in Figure 4 and is reversed to the outer elements which are in the position shown in Figure 3.

Figure 6 is a vertical section substantially on the line 6—6 of Figure 1.

Figure 7 is a bottom plan view looking up, of the shim shown in Figure 5 before the facing member is applied.

Figure 8 is a vertical section substantially on the line 8—8 of Figure 5.

Figure 9 is a side elevation of a modified form of shim.

Figure 10 is an end elevation of the shim shown in Figure 9.

Figures 11 and 12 are side elevations of the respective different elements forming the shim shown in Figure 9.

Figure 13 is a bottom plan view of the shim shown in Figure 9 with the facing members attached thereto.

Figure 14 is an enlarged vertical section of the shim taken substantially on the line 14—14 of Figure 9, and

Figure 15 is a side elevation of a part of a shim with one of the outer elements partly removed.

In the use of shim spacing elements for divided shaft bearings, particularly in connection with high speed and high pressure bearings as are

used in automotive and other engines it has been found desirable to affix a soft facing member 10 to the body element 12 to permit fitting of the shim closely to the shaft to prevent oil leaks from the bearings and yet not have the hard body of the shim score the shaft. Such shims must have the qualities of being readily formed so that the facing member of babbitt or similar material is firmly embedded or interlocked in the body portion 10 and will not drop out or be pounded out in hard wear or under severe operating conditions and will not become separated due to repeated heating and cooling of the bearing. It is furthermore essential that the shim be simply manufactured with the minimum amount of tools and die equipment and that the front face of the shim to which the babbitt is attached be uniform and planar to afford an even face for assembly in the die or mold when casting the facing thereon.

In the present construction which illustrates preferred forms of embodiment to which our invention is particularly susceptible we have shown a composite shim 12 which may be built up from a plurality of individual body elements 12a, 12b, and 12c, which may be of either solid or laminated construction as desired. These body elements are preferably all of the same outline and may be stamped from brass, steel or other suitable material in the same die. In the form shown, indentations are cut into the body portion forming tongues 14 in the nature of serrated block teeth, at a small angular inclination to the front face of the shim. The ends of all the tongues 14 are preferably all in alignment and constitute the front face 16 of the body of the shim. The body elements may be suitably perforated at 18 to receive the bearing bolt (not shown) and at 19 for centering the shim on the bearing dowels (not shown) as is the usual custom.

The tongues 14 are preferably of block form and in depth approximately equal to the distance between teeth although this may be varied if desired to give any desired support for the babbitt face.

Each of the shim body elements may also have a long lip portion 20 and a short lip portion 21 at each end of the body portion which lips are due to the angular relation of the teeth.

In assembling the shim, an odd number of body elements are preferably used and as shown, three in number is satisfactory. The center element 12b is the same as elements 12a and 12c but is merely reversed from the other elements 12a and 12c giving a resultant construction as shown in Figures 5 and 7. It will be noted that the lip portions 20 and 21 thus overlap and the tongues 14 also extend in opposite direction. This overlap thus forms inner recesses 22, not only between the respective teeth 14 on each element but between the overlapped portions of the teeth on the adjacent elements. Into these recesses 22, babbitt or similar metal is cast giving the resulting structure as shown in Figure 5 in which the facing member 10 projects into the recesses formed in the face of the body portion and extends in some portions 10a deep into the recesses 22 and becomes embedded between the respective body elements. The babbitt also projects into angular contact with the outer surfaces as shown at 10b in Figure 1 and at 10c on the extreme end of the teeth in such manner that the babbitt is firmly embedded and interlocked into the serrated teeth of the respective

body elements and will thus be securely held thereto.

The front faces of the teeth 14 are parallel and form an aligned front face 16 for the shim, such alignment permitting the body elements to be assembled readily in the casting die with the proper spacing and relation between the bearing bolt, which passes through the perforation 18, and the front line of the babbitt which contacts with the shaft. In other words the fixed size of the bearing is the distance between the bolt hole 18 and the front edge of the babbitt and if the body members are provided with a uniform front face 16 and there is a definite distance between the center of the bolt hole and the front face 16 the body portions can be accurately located in the die and the babbitt cast thereon will also be uniform and the bearings will all fit in the position intended. The rear faces 23 of the shims are also preferably plane surfaces although there is no necessary relation between the bolt hole 18 and the rear surfaces of the bearing, the rear surfaces being merely formed to provide substantial and sufficient backing in the bearing.

The angle of the tongues may be varied but a small angle is usually sufficient as the effectiveness of the angle is doubled due to the reversing of the intermediate body element. As may be noted in Figure 1, the babbitt engages the sides of the tongues of the respective body elements in such manner that it is doubly held and exerts a greater adhesion than would be the case if only a single row of tongues were used with double the angular deviation. It is also to be noted that the tongues 14 on the body element 12a, for example, of the outer body element overlap the tongues 14 on the body element 12b or the inner body element in such a manner that there can be no lateral movement of the facing member 10, which construction is more clearly shown in Figure 6. In this construction the facing 10 is substantially uniformly held at all points and there is no narrow or restricted neck of babbitt which might be easily broken to cause the facing to become separated from the body of the shim. The facing member is, of course, further locked due to the different angular faces of the teeth of the respective body elements which are reversed with respect to each other. In such a construction it is not essential to make the body laminations of metals to which the facing metal will closely adhere, as the facing metal is closely surrounded on all but the front side and can not therefore come loose.

The casting of the shim is readily accomplished by a preliminary alignment of the body elements and the openings are sufficiently large so that the cast metal will readily flow into the openings. There are no pockets and the metal will flow freely into contact with all parts of the shim.

A slightly modified form of construction is shown in Figures 9 and 15 inclusive in which the body elements of the shim, although they are of slightly different configuration, are nevertheless of the same general dimensions and may be made in the same die by a slight variation of the inserts. The assembled shim 25 is shown in Figure 9 to which has been applied a suitable facing of babbitt or similar metal 26. In the particular instance the babbitt facing has been applied only to the ends, leaving a central opening 27 which may effectively operate as an oil reservoir on the shaft. It is obvious, however, that the babbitt may extend across the face of 150

the shim as shown in Figure 1, and also that the facing member in Figure 1 may be applied only at the ends if desired.

In this second form of embodiment of the invention the body elements 28 and 29 which may be of either solid or laminated construction, are of substantially the same major dimensions, and the shape of the front edge 30, of the intermediate and the outer body members is varied.

10 The body portion of the shim 28 is provided with a pair of laterally extending arms 31 which are provided with keystone shaped elements 32, which are preferably provided with apertures 33 for a purpose to be hereinafter described. The body portion of the shim 28 is provided with a key-15 stone portion 34 having the front face 30 with which the keystone elements 32 are in alignment forming the front face of the body portion. The keystone of the body portion 34 cooperates with 20 the keystone elements 32 in such a manner that the opening formed is of greater dimensions on the inside and has a slightly restricted neck due to the ends 35 which tend to anchor the babbitt facing member 26.

25. The second body element 29 is provided with similarly extending arms 31 and has a similar keystone portion 34 and the arms each have a depending tooth 36. The depending teeth or 30. angular elements 36 are preferably at reverse angles and thus face each other. The resulting construction thus has a plurality of openings 37 which are of greater width on the inside than on the outside due to the ends 35 on the keystone body portion 34 and the ends of the angular 35. teeth 36.

A preferable assembled construction includes top and bottom body members 28 and a central body element 29 sandwiched therebetween. In such construction the face of the body member 40 presents a plurality of irregular openings, all of which have a greater width in their inner portion than the outer edge which has the reduced neck. When cast the bearing metal flows into the irregular openings resulting in the shim construction shown in Figures 9 and 14. The Babbitt metal 26 fills the apertures 33 and enters into the bottom of the recesses 32a and 37. The depending teeth 36 cooperate with the keystones 45 32 and in turn the teeth 36 and the keystones 32 50 cooperate with the keystone shape of body portion 34 to securely retain the babbitt in position. The complete shim is shown in bottom plan view in Figure 13 and in end view in Figure 10. In Figure 15 the shim is shown with a portion 55 of the outer lamination 28 broken away showing the internal extension 31 and tooth 36 and the babbitt in the aperture 33. It will be seen that the irregular form of the babbitt is securely interlocked to the shim body elements and 60 embedded in such a manner that it can not be accidentally loosened.

The alignment of the front edge of the shim is similar to that shown in the first form. The edge of each of the respective keystones is in proper relation to the bolt hole 18 which is similarly true of the ends of the respective teeth 36 in the intermediate body element. With such an arrangement it is possible to control the size of the shim and the relation of the edges of the cast metal with respect to the center of the bolt hole to within very fine limits and there can be no maladjustment or accidental slippage of the parts. The material is firmly embedded in the shim and cannot move transversely to the plane of the shim due to the inter-relation of the de-

pending teeth 36 and the keystones 32. The Babbitt metal cannot pass longitudinally away from the shim because of the angular relation of the keystones and additionally because of the Babbitt metal which extends into the apertures 33. These apertures tend to assist in compacting and securing of the shim body elements to each other and aid in maintaining the proper thickness and integral relation of the built-up shims.

It is to be understood that throughout this specification the use of the word "babbitt" is intended to cover suitable alloys which may be used in connection with the facing of shims and which will not score rapidly rotating shafts when brought in contact therewith and is not intended to limit the facing material to any definite "babbitt" alloy. The shim body is usually made of a hard material such as brass, and may be made of steel and it is also to be understood that although a single bolt hole is shown it is possible by a rearrangement of the body portion to have a plurality of bolt holes and the outline of the shim will follow the bearing caps as is well known in the art. It is also to be understood that although three laminations are shown, a larger number could as readily be used and thin laminae for peeling could also be provided if desired. 90 95 100

While we have shown preferred forms of embodiments to which our invention is particularly adapted we are aware that other modifications may be made therein and we therefore desire a broad interpretation of our invention within the scope and spirit of the disclosure and of the claims appended hereinafter. 105 110

We claim:

1. A shim for split bearings of the class described comprising a plurality of stacked body elements, each of said elements having regular angular projections, one of said body elements being reversed with respect to the other body elements, to form a plurality of depressions partially overlapped in a plane transverse to the body portion, all of said body elements forming a plurality of reduced neck depressions on the edge, the front edge of said depressions being in alignment, and a facing member embedded in said depressions.

2. A bearing shim for split bearings of the class described, comprising a plurality of body members, each of said body members having angular projecting serrated teeth, one of said body elements being reversed with the teeth projecting in a direction opposite to that of the remaining teeth, said teeth of all said body elements being in alignment along the front of the shim and forming internal irregular depressions and a facing member embedded in said depressions and in interlocking engagement with said teeth whereby said facing is held irremovable with respect to the body element. 125 130 135

3. A bearing shim for split bearings of the class described, comprising a plurality of body members, each of said body members having angular projecting serrated teeth, said teeth of all said body elements being in alignment along the front of the shim and forming internal depressions partially overlapped by said teeth, and a facing member embedded in said depressions and in interlocking engagement with said teeth whereby said facing is held irremovable with respect to the body elements. 140 145

4. A composite shim for split bearings of the class described, a body element having a plurality of keystone elements, a second body element 150

- having a plurality of keystone openings in a staggered relation to and overlapping the keystone elements of the other body element, the body elements being stacked with different body elements adjacent each other, said keystone elements forming a plurality of irregular shaped openings and a facing member embedded in said openings. 80
5. A shim of the type described comprising a laminated body member and a facing member, the respective laminations of said body member, having similar extensions forming indentations, the indentations of one lamination overlapping body member extensions in the other laminations, to form an irregular system of connected indentations to receive a facing member said facing member inter-engaging with the overlapping indentations. 85
6. A shim including a plurality of superposed hard metal body portions having depending serrated teeth, certain of the teeth being angularly disposed with respect to other teeth, said teeth forming recesses and other teeth overlapping said recesses, and a bearing metal facing member at one edge of the body engaging the registering recesses of all of said body portions, whereby said facing member is immovable in either the plane of or plane perpendicular to the shim. 90
7. A shim comprising an odd number of laminations all of the laminations being of substantially the same shape and size in their principal dimensions, each of said laminations having regular angular projections and recesses, said laminations being assembled with the angular projections reversed and the projections of one lamination overlapping the recesses of another lamination and forming interlocking indentations, and a facing member embedded in said indentations. 100
8. A shim as claimed in claim 7 in which the laminations are identical, the center lamination being reversed with respect to the outer laminations to form overlapping interlocking recesses. 110
9. A composite shim having a hard body portion and a soft facing portion non-removably secured thereto, said body portion being composed of a plurality of separate body members each having recesses in the front face thereof which are in staggered relation with the recesses in the adjacent body members, the facing portion having projecting portions which extend into each of said recesses to thereby interlock said facing portion to the body portion in two planes. 120
10. In a composite shim of the type described a hard body portion consisting of a plurality of stacked body members each body member having a plurality of recesses with intervening tongues, said body portions being assembled with the recesses of one body member opposite to the tongues of the adjacent body member, and a facing member having projections extending into each of said recesses in the body member. 125
11. In a composite shim of the type described a hard body portion consisting of a plurality of stacked body members, each body member having a plurality of recesses with intervening tongues, said body portions being assembled with the recesses of one body member opposite to the tongues of the adjacent body member, a facing member having projections extending into each of said recesses in the body member, and means on some of the projections of said facing member to hold said members in assembled relation. 130
12. As an article of manufacture of the class described a bearing shim comprising a plurality of different shaped body elements having substantially identical over all major body dimensions, portions of said body elements forming indentations, the indentations being open transverse to the face of the body portions, and other portions partially overlapping said indentations, the indentations of the different body members having reduced neck portions internally open to the sides, and a facing member interlocked in said indentations. 135
